MOLDED FOOD PRODUCT

Leo Peters, Evanston, Ill.

Application January 11, 1952, Serial No. 18,005

Term of patent 14 years

(Cl. D82—2)

To all whom it may concern:

Be it known that I, Leo Peters, a citizen of the United States, residing at Evanston, county of Cook, and State of Illinois, have invented a new, original, and ornamental Design for a Molded Food Product, of which the following is a specification, reference being had to the accompanying drawing, forming a part thereof, in which:

Fig. 1 is a perspective view of a molded food product showing my new design; Fig. 2, a top plan view; Fig. 3, a side elevational view; Fig. 4, a side elevational view taken from the side opposite that shown in Fig. 3; and Fig. 5, a bottom plan view thereof.

I claim:

The ornamental design for a molded food product, as shown.

LEO PETERS.
